(57) **CLAIM**

I claim the ornamental design for a headset, as shown and described.

DESCRIPTION

FIG. 1 is a rear, top, left perspective view of a headset in an open configuration, showing our new design;

FIG. 2 is front, bottom, right perspective view thereof;

FIG. 3 is a front elevation view thereof;

FIG. 4 is a rear elevation view thereof;

FIG. 5 is a right side view thereof;

FIG. 6 is a left side view thereof;

FIG. 7 is a top plan view thereof;

FIG. 8 is a bottom plan view thereof;

FIG. 9 is a front, top, right perspective view of the headset shown in FIG. 1 in a closed configuration;

FIG. 10 is a front elevation view thereof;

FIG. 11 is a rear elevation view thereof;

FIG. 12 is a right side view thereof;

FIG. 13 is a left side view thereof;

FIG. 14 is a top plan view thereof; and,

FIG. 15 is a bottom plan view thereof.

The broken lines shown in the drawings illustrate portions of the headset that form no part of the claimed design.
